(57) **CLAIM**

The ornamental design for a soap dispenser, as shown and described.

DESCRIPTION

FIG. 1 is a perspective view of a soap dispenser showing our new design;

FIG. 2 is a top plan view thereof;

FIG. 3 is a bottom view thereof;

FIG. 4 is a first side view thereof, the opposite side being a mirror image of the side shown;

FIG. 5 is a front elevational view thereof; and,

FIG. 6 is a rear view thereof.
